Assistant Examiner—Gregory Andoll

(21) Appl. No.: **29/135,459**

(57) **CLAIM**

(22) Filed: **Jan. 12, 2001**

The ornamental design for a retractable spike shoe, as shown
and described.

(51) **LOC (7) Cl. 02-04**

DESCRIPTION

(52) **U.S. Cl. D2/912; D2/911; D2/910;**

FIG. 1 is a front elevational view of the retractable spike
shoe of the present invention;

D2/909; D2/906

FIG. 2 is a rear elevational view of the retractable spike shoe
of FIG. 1;

(58) **Field of Search D2/970, 909-912,**

FIG. 3 is a left side elevational view of the retractable spike
shoe of FIG. 1, the right view being mirror image thereof;
FIG. 4 is a top plan view of the retractable spike shoe of FIG.
1;

D2/904-906, 943, 944, 947-960; 36/127,

FIG. 5 is a bottom plan view of the retractable spike shoe of
FIG. 1;

83, 113, 114, 134, 136, 45, 50.1, 59 R

FIG. 6 is a top, front, left side perspective in an alternate
position (key extended); and,

5,337,494 A 8/1994 Ricker

FIG. 7 is a top, front, left side perspective in yet another
alternate position (spikes retracted and key flush).
